UNITED STATES PATENT OFFICE.

JOHN F. CARD, OF THREE RIVERS, MICHIGAN, ASSIGNOR TO SHEFFIELD CAR COMPANY, OF THREE RIVERS, MICHIGAN.

FAN.

1,100,053.

Specification of Letters Patent. Patented June 16, 1914.

Application filed October 4, 1912. Serial No. 723,886.

To all whom it may concern:

Be it known that I, JOHN F. CARD, a citizen of the United States, residing at Three Rivers, Michigan, have invented certain new 5 and useful Improvements in Fans, of which the following is a specification.

This invention relates to improvements in fans.

My improvements are particularly designed by me for circulating air through 10 electric motors, and I have shown the same as embodied in an electric motor, although my improvements are desirable for and may be readily adapted for use in other 15 relations.

The main object of this invention is to provide an improved fan structure which is very effective and at the same time, is simple in structure and not likely to get out of 20 repair in use.

Further objects, and objects relating to structural details, will definitely appear from the detailed description to follow.

I accomplish the objects of my invention 25 by the devices and means described in the following specification. The invention is clearly defined and pointed out in the claims.

A structure which is a preferred embodiment of my invention is clearly illustrated 30 in the accompanying drawing forming a part of this specification, in which:

Figure I is a side elevation of a motor embodying the features of my invention. Fig. II is a detail longitudinal section on a 35 line corresponding to line 2—2 of Fig. III, the motor shaft 4 being shown in full lines. Fig. III is a cross section on a line corresponding to line 3—3 of Fig. II. Fig. IV is a plan of one of the fan blade blanks. 40 Fig. V is a perspective view of one of the blades.

In the drawing, similar reference characters refer to similar parts throughout the several views, and the sectional views are 45 taken looking in the direction of the little arrows at the ends of the section lines.

Referring to the drawing, the casing 1 is provided with a central body portion and end portions 2 and 3 having suitable bearings 50 therein for the shaft 4. The end portions 2 and 3 are provided with openings for the circulation of air. The electrical connections are not illustrated. The armature core 5 is mounted on the shaft 4 to revolve therewith. 55 The mountings of the poles 6 are not illus-

trated as they form no part of this invention.

The core 5 is provided with a ring-like flange 7, the inner edge of the flange being spaced from the shaft as illustrated. The 60 fan blades 8 are formed of sheet metal and are provided with integral body portions 9, the body portions being segmental in shape and arranged upon the ring edge to edge as shown in Fig. III. The length of the body 65 portions is substantially the width of the flange. The body portions are provided with integral securing fingers 10 which are folded over the edges of the flange for securing the blades thereto. The body portions are provided with integral fingers 10 which are folded over the edges of the ring. 70 Each body portion is preferably provided with three fingers, one at the inner end of the body and one at each side on the blade, 75 as in the structure illustrated. These fingers are firmly clamped over the edges of the ring and secure the blades thereto very effectively and so that they do not become loosened by the vibration of the motor in 80 use. This is, of course, a highly advantageous feature. The motor casing is provided with an internal annular rib 11 in the plane of the flanges, the outer ends of the blades revolving close to the edge of the rib. This 85 is found to be of advantage in directing the current of air.

I have illustrated and described my improvements in a simple embodiment in which I have adapted the same. I have not attempted to illustrate or describe the various modifications possible and which I contemplate, as such modifications will be readily understood by those skilled in the art to which this invention relates from the disclosure made.

Having thus described my invention, what I claim is new and desire to secure by Letters Patent is:

1. The combination of a casing, a rotor having a ring-like flange thereon, the inner edge of the flange being spaced from the rotor shaft; and a plurality of sheet metal fan blades provided with integral segmental body portions arranged on said flange edge to edge and having integral securing fingers at their inner ends and at each side of the blades folded over the edges of the flange for securing the blades thereto, the length of said body portions being substan- 110

tially the width of the flange, said casing being provided with an internal annular rib in the plane of the flange, the outer ends of the blades revolving close to the edge of the rib.

2. The combination of a casing, a rotor having a ring-like flange thereon, the inner edge of the flange being spaced from the rotor shaft; and a plurality of sheet metal fan blades provided with integral segmental body portions arranged on said flange edge to edge and having integral securing flanges at their inner ends and at each side of the blades folded over the edges of the flange for securing the blades thereto, the length of said body portions being substantially the width of the flange.

3. The combination of a casing, a rotor having a ring-like flange thereon, the inner edge of the flange being spaced from the rotor shaft; and a plurality of sheet metal fan blades provided with integral body portions arranged on said flange and having integral securing fingers folded over the edges of the flange for securing the blades thereto, said casing being provided with an internal annular rib in the plane of the flange, the outer ends of the blades revolving close to the edge of the rib.

30 4. The combination of a casing, a rotor having a ring-like flange thereon, the inner edge of the flange being spaced from the rotor shaft; and a plurality of sheet metal fan blades provided with integral body portions arranged in a radial plane on said

flange and having integral securing fingers folded over the edges of the flange for securing the blades thereto.

5. A structure of the class described, comprising a ring and sheet metal fan blades provided with segment shaped body portions arranged on said ring edge to edge and provided with integral fingers clamped over the edges of the ring, each blade body portion being provided with a finger at its inner end and a finger at each side of its blade, the width of the rim being substantially the length of the blade body portions.

6. A structure of the class described comprising a ring and sheet metal fan blades provided with segment shaped body portions arranged on said ring edge to edge and provided with integral fingers clamped over the edges of the ring, each blade body portion being provided with a finger at its inner end and a finger at each side of its blade.

7. A structure of the class described, comprising a ring, and sheet metal fan blades provided with complementary - segment shaped body portions arranged in a radial plane on said ring edge to edge and provided with integral fingers clamped over the edges of the ring.

In witness whereof, I have hereunto set my hand and seal in the presence of two witnesses.

JOHN F. CARD. [L. S.]
